Kenwood Corporation, "Kenwood Speaker Bracket," (Product Name: SK-300S), available at https://www.kenwood.com/jp/products/car-audio/speaker_amp/blacket/skx_300s/, published at least on Mar. 1, 2016, 3 pages.*Primary Examiner* — Sandra Snapp*Assistant Examiner* — Ieisha N Price(74) *Attorney, Agent, or Firm* — Faegre Drinker Biddle & Reath LLP(57) **CLAIM**

The ornamental design for the bracket for automobile speaker, as shown and described.

DESCRIPTION

FIG. 1 is a perspective view of a bracket for automobile speaker showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the bracket for automobile speaker is included for the purpose of illustrating portions of the bracket for automobile speaker and forms no part of the claimed design.
